COLLECTION RECEPTACLE FOR EMPTYING MOTOR VEHICLE ASH TRAYS

Thomas H. Kiernan, 1106 Redbud Hill Apts.,
Bloomington, Ind. 33964

Filed Mar. 20, 1967, Ser. No. 6,288

Term of patent 14 years

(Cl. D49—30)

Fig. 1.

Fig. 3.

Fig. 2.

Fig. 4.

Fig. 5.

FIG. 1 is a side elevational view of a collection receptacle for emptying motor vehicle ash trays showing my new design, the opposite side being a mirror image of the side shown;

FIG. 2 is a top plan view;

FIG. 3 is a front elevational view;

FIG. 4 is a rear elevational view; and

FIG. 5 is a bottom plan view thereof.

I claim:

The ornamental design for a collection receptacle for emptying motor vehicle ash trays, as shown and described.
